UNITED STATES PATENT OFFICE.

HARRY RAYMOND COLLINS, OF ALLENTOWN, PENNSYLVANIA, ASSIGNOR TO FULLER-LEHIGH COMPANY, A CORPORATION OF PENNSYLVANIA.

PULVERIZER-MILL.

1,386,093.

Specification of Letters Patent.

Patented Aug. 2, 1921.

Application filed September 9, 1920. Serial No. 409,069.

To all whom it may concern:

Be it known that I, HARRY R. COLLINS, a citizen of the United States, residing at Allentown, in the county of Lehigh, State of Pennsylvania, have invented certain new and useful Improvements in Pulverizer-Mills; and I do hereby declare the following to be a full, clear, and exact description of the invention, such as will enable others skilled 10 in the art to which it appertains to make and use the same.

This invention which relates to pulverizing mills has for its general object the improvement of pulverizing mills of the type 15 shown, for example, in United States patents to J. W. Fuller, Nos. 849,779, 9,922,468 and 1,039,721. In such mills there is a race-way having a number of pulverizing balls therein propelled by a series of pushers, and 20 the pulverized material is removed upward from the grinding zone largely by the suction of inclined blades which lift the finely pulverized material into the field of a super-jacent series of fan blades by means of which 25 the material is discharged from the mill.

More specifically considered the present invention relates to improvements in a pulverizer mill of the type shown in my co-pending application Serial No. 336,571, filed 30 November 8, 1919, wherein there is provided a pulverizing mill and air separator unit of improved construction in which all of the moving parts including the fan for producing circulation through the separator and 35 also the feeder are driven from a common shaft connected to a suitable source of power so that their speeds are dependent upon the speed of the mill and variations in the latter are accompanied by corresponding variations 40 in the speed of the other parts of the apparatus. Thus a more uniform operation of the apparatus may be obtained, and the necessity for independent regulation of the speed of the fan and feeder in accordance 45 with variations in speed of the mill is eliminated. In the mill of my co-pending application referred to above, the several sections of the casing are mounted one above another and carried by a casting resting directly upon the foundation of the mill and the grinding zone is located immediately above the casting so that vibration caused by the moving parts is reduced to a minimum.

50 As distinguished from the usual form of

Fuller mill, the mill of my co-pending application contains a relatively short main-shaft which is supported entirely from the lower casing of the mill and is driven from the main counter shaft of the mill by suitable gears. The yoke which carries the arm upon which the pushers are mounted for propelling the grinding balls is set on the end of the shaft in such a manner that it may be conveniently lifted therefrom and removed through one of the upper sections 60 of the mill casing, and the grinding balls and some of the members of the upper bearing of the main shaft may also be removed through this same door. The yoke itself 65 involves several improvements in its details of construction, particularly the manner of supporting the pushers upon the arm of the yoke and the arrangement for detachably connecting to the body of the yoke the blades 70 for lifting the pulverized material from the zone of action of the balls.

The air current for conveying the pulverized material from the mill to the separator of the unit is produced by a fan 80 mounted at the top of the mill casing and the flow of pulverized material laden air into the zone of operation of the fan and from thence to the conduit leading to the air separator is controlled by a lantern-like 85 damper provided with means by which it may be adjusted from the outside of the mill.

In the mill shown in my co-pending application, the grinding ring is mounted within 90 a base section which rests directly upon the foundation of the mill, and mounted upon the top of the grinding ring is another section surrounded by a casing into which the air returns from the separator 95 and from which it is directed into the mill by tangential blades extending between the top and bottom of this section. Above the section provided with the tangential blades is a central section in which is located the 100 door through which the grinding balls, the yoke and other internal parts of the mill may be removed. On top of the central section is another section to the top of which is attached a casing containing the fan for 105 producing circulation of air through the mill and the conduit leading to the separator.

The lower bearing of the main-shaft and the gears which drive this shaft are mounted within a cellar section which is detach- 110

ably connected to the bottom of the base section and may, therefore, be removed to permit access to the mechanism contained within this cellar section. In order, however, to remove a worn grinding ring and replace it by a new one, it is necessary to raise the several sections which constitute the portion of the casing lying above the base section a sufficient distance to permit 5 the grinding ring to be lifted out of the base section. Such removal of the upper sections of the mill requires that the conduits which connect the mill to the air separator of the unit be disconnected, and it is also 10 necessary to provide a crane or other lifting apparatus for raising the heavy upper sections of the mill.

In accordance with the present invention the grinding ring is mounted directly upon 20 the base of the mill, and the upper sections rest directly upon the top of the grinding ring. Surrounding the grinding ring and connected between the base section and the bottom of the section immediately above 25 the ring is a number of bolts adapted to serve as jacks by means of which the upper sections of the casing may be raised sufficiently to permit the grinding ring to be slipped out from between these sections and 30 the base upon which it rests. It is therefore required that the upper sections of the mill be raised only a comparatively short distance, so that it is not necessary to disconnect the conduits between the mill and 35 the separator, and the use of cranes or other lifting devices is avoided.

In order that the grinding ring may be withdrawn sidewise, it is necessary to first 40 remove the grinding balls, the yoke and the shaft which extends through the ring. The balls and the yoke may be removed through the door in one of the upper sections of the casing, and in order that the shaft may be withdrawn from the ring, it and both its 45 upper and lower bearings are carried upon the cellar section of the mill so that by dropping the latter the shaft may be withdrawn from the grinding ring, leaving the latter free to be slipped from between the base 50 and the upper sections of the mill as described above.

In order to permit the cellar section with the main shaft to be lowered, the counter shaft which carries one of the driving gears 55 for the mill, is arranged so that it may be moved lengthwise to withdraw its inner end from a bearing in the cellar section of the mill.

The present invention also comprises a 60 number of other improvements in certain features of the mill, such as the lifting blades that are mounted upon the yoke and the damper for controlling the current of air laden with pulverized material that passes 65 through the mill. The particular nature of

these improvements as well as other objects and advantages of the invention as a whole will appear more clearly from a description of a preferred embodiment thereof as illustrated in the accompanying drawings, in 70 which:—

Figure 1 is an elevation of the mill partly in cross section and partly as seen from the outside;

Fig. 2 is a sectional elevation of the lower 75 part of the mill;

Fig. 3 shows the position occupied by the several elements constituting the lower portion of the mill when the grinding ring is being removed; 80

Fig. 4 is a transverse sectional view along the line 4—4 of Fig. 3;

Fig. 5 is a transverse sectional view along the line 5—5 of Fig. 1 showing the top of the yoke in plan and the surrounding cas- 85 ing in section;

Fig. 6 is a detail view of one of the devices for preventing creeping of the grinding ring; and

Fig. 7 is a view of the bottom of the 90 damper, the surrounding casing being shown in section along the line 7—7 of Fig. 1.

Referring to the drawings in which similar reference characters denote similar parts throughout the several views, 10 represents 95 the foundation of the mill which is provided with a pit 11 into which the cellar section of the mill may be lowered as will herein-after appear. Upon the foundation is mounted a base 12 provided with radial pas- 100 sageways 13 closed at their outer ends by suitable caps 14. The grinding ring 15 rests directly upon the top of the base and is prevented from moving sidewise by means of an annular ridge 16 fitted within a cor- 105 respondingly shaped groove in the top of the base.

Resting upon the top of the grinding ring is a port section 17 which is provided with an annular groove adapted to fit over a cor- 110 responding tongue 18 at the top of the ring. The port section 17 is surrounded by a return air chamber formed by a casing 19 to which is connected a conduit 20 through which the air returns from the separator 115 to the mill. The return air is directed into the mill by substantially tangential blades or partitions 21 extending between the top and bottom of the port section as shown most clearly in Figs. 1, 2, and 5. The return 120 air chamber casing 19 is provided with apertures to permit access to the interior of the casing for cleaning and repairs, these apertures being closed by suitable covers 22.

On top of the port section 17 is a central 125 section 23 provided with a door 24 through which access may be had to the interior of the mill for the purpose of cleaning the same or removing or repairing the yoke or grinding balls. Mounted upon the exterior 130

of this section is a feeder which is here shown of the same type as that shown in my co-pending application referred to above, but which may be of any other suitable construction. As described in detail in that application, this feeder comprises a casing 26 connected to the main casing and carrying a shaft from which is suspended a member having a curved portion upon which material falls from a supply hopper 27, and also a sweeping portion. When the shaft is oscillated, material is discharged from the curved portion upon the bottom of the feeder casing and then pushed into the passage-way leading to the main casing by the sweeping portion. As shown in Fig. 1 herein, the feeder shaft is provided with an arm 28, and there is an adjustable and eccentric connection 29 between the arm and a counter shaft 30 mounted in a bracket 31 attached to the outside of the mill section 23 and connected by means of a belt 32 to a second counter shaft 33, mounted in a bracket 34 likewise attached to the exterior of the section 23. Shaft 33 is driven from the main counter shaft of the mill by a belt 35. Since the feeder constitutes no part of the present invention it will not be described in further detail.

On top of the central section 23 is a flaring section 36 to which is attached a cover section 37, provided with bracing ribs 38 adapted to register with corresponding ribs 39 on the section 36. Upon the top of the cover section 37 is mounted a fan casing 40 which is also provided with bracing ribs adapted to register with the bracing ribs of the cover section to produce a strong mounting for the fan and its casing. Connected to the fan casing is a conduit 41 through which the air laden with pulverized material is conducted to an air separator which, since it forms no part of the present invention, is not shown on the drawings. Mounted upon the top of the fan casing is a tripod 42 provided at its apex with a cylindrical socket 43 which contains a self-oiling vertical bearing 44 from which is suspended a shaft 45 entering the fan casing 40 through a cover plate 46, which on its upper face, is provided with a bearing 47 of any suitable construction to prevent lateral displacement of the shaft, this bearing being preferably provided with a well adapted to be filled 55 from an oil cup outside the bearing. Mounted upon the lower end of the shaft 45 within the casing 40 is a fan 48, of any suitable construction. The shaft is provided with a pulley 49 around which passes a belt 50 running to the main counter shaft of the mill. In order to change the direction of the belt, it is passed over pulleys 51 mounted in a bracket 52 attached to the fan casing. The tension of the belt may be controlled by 65 means of an idler 53 adapted to be moved forward or away from the belt by a hand wheel 54. The idler is preferably mounted upon an extension of the base 12, as shown most clearly in Fig. 1.

For controlling the amount of air laden with pulverized material which is drawn from the casing of the mill by the fan 48, there is provided a lantern like damper which, as shown most clearly in Fig. 1, comprises a cylindrical member 55, provided 70 with ports 56 and attached to a flange 57 at the aperture in the cover section 37. Encircling the member 55 and supported upon a ledge 58 at the bottom of this member is a movable cylindrical member 59 provided 75 with ports 60 which may be brought more or less into registry with the ports 56 of the upper member in accordance with the amount of air which it is desired shall pass through the damper. The movable member 80 59 is provided with lugs 61, preferably arranged diametrically opposite to each other, to which are connected rods 62 which pass through bushings 63 in the cover section 37. By manipulation of the rods the position of 85 the movable member 59 with relation to the fixed member 55 may be adjusted to control the extent of the openings through the wall of the damper.

The damper described above is constructed 90 substantially the same as shown in my co-pending application Serial No. 336,571, but in accordance with the present invention, the bottom of the damper is provided with apertures 64, as shown most clearly in Fig. 7. 95 Mounted within the damper and upon its bottom is a circular plate 65 provided with corresponding apertures 66. The plate 65 carries a lug 67 extending through a slot in the wall of the fixed member 55 and to 100 which is attached a rod 68 passing through the wall of section 36 and by means of which the plate 65 may be manipulated to bring the apertures 66 therein more or less into registry with the aperture 64 in the bottom 105 of the fixed member of the damper. There is thus provided mechanism by which the amount of air laden with pulverized material that passes to the fan casing may be closely controlled, and the ports in the bottom of the damper may be controlled independently of those in its wall.

Attached to the bottom of the base 12, is a cellar section or gear housing 70 provided at one side with an opening into which is 110 fitted a plate 71 which carries a bearing 72 for a main counter shaft 73 slidably mounted in a bearing 74 on a pedestal 75. The shaft carries a pulley 76 adapted to be connected by a belt to a suitable source of power, and also a second pulley 77 over which the belt 50 for driving the fan 48 passes. The belt 35 for driving the feeder may pass directly around the shaft or around a small pulley 78 upon the shaft.

The plate 71 is connected with a chamber 79 forming an oil well beneath the bearing 72. The main counter shaft 73 carries a collar 80 adapted to lift the oil from the well 5 and allow it to flow through ducts 81 to the interior of the bushing of the bearing. The inner end of shaft 73 is adapted to be supported within a bearing 82 set in a socket formed in the interior of the cellar section 10 of the mill. Near the end of the shaft is a bevel-pinion 83 adapted to mesh with a bevel-gear 84 attached to an enlarged portion 85 of the main shaft 86. The enlargement 85 is formed with a tapering portion 15 over the lower end of which the hub of gear 84 fits, while a collar 87 fits over the upper portion and is clamped to the gear by bolts to hold the gear firmly upon the shaft.

The weight of main shaft 86 and the parts 20 mounted thereon is borne by a step bearing at the lower end of the shaft and a bearing beneath the hub of bevel-gear 84. The step bearing is located in an extension 88 of the cellar section 70 and comprises an adjustable 25 bronze disk 89 and a steel stud 90 at the lower end of the shaft. A bushing 91 detachably mounted within the extension 88 prevents displacement of the lower end of the shaft. Above the bushing 91 is a bridge 30 piece 92 upon which is mounted a member 93 which serves as a bearing for the hub of bevel-gear 84. This bearing is so constructed and proportioned with respect to the bearing at the bottom of the mill as to aid 35 in carrying the weight of the shaft and the parts mounted thereon.

Mounted upon the top of the cellar section 70 and adapted to be clamped between the latter and the base 12 is a conical shaped 40 member 94 upon the top of which is a bearing 95 for the upper end of the main shaft. This bearing is held in alignment with the lower bearing of the shaft by an inner ring 96. At the bottom of bearing 95 is a duct 45 97 (see Fig. 3) leading to a pipe 98, adapted to be detachably connected to a pipe 99 which passes through one of the passageways 13 in the base 12 and carries at its upper end an oil cup 100 which may be additionally supported by means of a bracket 50 101 attached to the bottom of casing 19. The pipe 99 may be surrounded at the point where it passes out of the passageway 13 by a suitable bushing 102 to prevent escape 55 of material through this passageway. Duct 95 may be provided with a suitable drain cock 103, and at its inner end it is connected with a circular port 104 through which oil 60 may enter the chamber within the bearing 95. The main shaft 86 rotates within a bronze bushing 105 which at its upper end is provided with an outwardly extending shoulder 106 adapted to be attached to a ledge 107 within the bearing 95. A collar 65 108 is clamped upon shaft 86, and if desired

a packing ring may be placed between the collar and the top of bushing 105 to prevent the entrance of dust into the top of the bearing.

The bushing 105 may be provided with 70 any number of apertures to permit oil to flow between it and the main shaft. At the bottom of the bushing is a packing ring 109 which is held in place by a gland 110 surrounding the main shaft and adapted to be 75 pressed against the ring by a pair of cams 111 upon pivots 112 projecting from the ring 96. The lower ends of the cams are connected to a yoke 113 to which is attached a rod passing through the member 94 and 80 the wall of the base 12 and provided at its outer end with a nut by which the position of the rod and consequently the pressure of the gland against the packing ring may be adjusted to hold the ring against the bottom of the bearing and prevent the entrance 85 of any material into the bearing or leakage of oil therefrom.

The upper end of main shaft 86 is tapered as at 114 and upon this tapered end is fitted 90 a yoke 115 which is provided with a depending portion closely surrounding the upper bearing of the shaft to lessen the tendency of pulverized material to penetrate into the bearing. At the top of the yoke is 95 a plate 116 which is fastened to the end of the main shaft to prevent the yoke from being lifted during the operation of the mill.

Projecting outward from the bottom of 100 the yoke are pusher arms 117 of which four are used in the embodiment shown herein although it will be understood that any other desired number may be provided. The pusher arms are adapted to carry pushers 105 for propelling the grinding balls 118, but since the construction of the arms and the pushers constitute part of the invention of my copending application Serial No. 336,571, 110 they have not been shown in detail herein. 110

Mounted upon the yoke 115 above the zone of action of the grinding balls are lifting blades 119 each having its outer edge bent upwardly as at 120 and provided with such a curvature as will throw the pulverized material toward the center of the mill thus preventing relatively large particles which may be lifted by the blades from being carried out of the mill by the current of air entering through the ports of the section 17 120 which surrounds the lifting blades. The inner edge of each blade is connected to a bracket 121 which is provided with a vertical rib 122. Suitable bracing ribs 123 are provided beneath the underface of the blade 125 119 to aid in supporting the latter. The bracket 121 and its ribs are connected to a member 124, having a sloping face, which is adapted to fit within a pair of parallel sloping guideways 125 projecting from the 130

side of the yoke substantially midway between two of the pusher arms 117 so that the blades 119 will lie above and midway between two of the grinding balls 118. The 5 two guide-ways 125 of each pair are connected at their bottoms by a shelf 126 upon which the corresponding member 124 is seated to hold its lifting blade in place on the yoke. To prevent the blade from being 10 raised during the operation of the mill a pin 127 is inserted through apertures in the top of the guide-way. In order to aid in dislodging the blade the guideways may be provided at their lower ends with apertures 15 into which may be inserted a pointed pin as described in my copending application No. 336,571, these apertures being located partly above the shelf 126 which is provided with a groove 128 corresponding to 20 the lower part of the aperture so as to permit the pin to be driven through these parts to dislodge the lifting blade to permit it to be more easily removed.

The arrangement of the yoke and parts 25 associated therewith upon the upper end of the main shaft 86 permits any of the members mounted thereon as well as the body of the yoke and the grinding balls 118 to be lifted out of the mill through the door 24 30 in the casing section 23. After the yoke has been removed access may be obtained to the upper bearing for adjusting and repairing in case the cellar section with the main shaft mounted thereon is not lowered into 35 the position shown in Fig. 3.

After continuous service the grinding ring becomes worn and it is necessary to remove it and insert a new one. To permit this to be done it is necessary to lift the upper 40 sections of the casing and for this purpose there is provided a number of bolts 130 connected between the base 12 and a flange 131 projecting from the bottom of the port section 17 of the mill. Each of these bolts is 45 clamped to the base 12 by means of a pair of nuts 132 and to the flange 131 by means of a pair of nuts 133. As the bolts surround the grinding ring it is necessary that some of them be removed when the ring is to be 50 taken out, and for this purpose there is provided an arrangement for detachably connecting the bolts to the base 12 and the flange 131.

As shown most clearly in Fig. 4 the base 55 is provided with tongues 134 each having a radial slot 135 adapted to receive the shank of the bolt and a circular recess 136 concentric with the slot and adapted to receive a washer 137 placed below the upper one of 60 the pair of nuts 132. A second washer 138 may be employed in connection with the lower nut of this pair, but this washer bears directly against the smooth lower face of the lug 134. As shown most clearly in Fig. 5 65 the flange 131 of the port section is provided

with similar radial slots 139, and concentric with each of the slots at the top of the flange is a circular recess 140 adapted to receive a washer 141 as shown most clearly in Fig. 2. There is thus provided an arrangement by 70 which each of bolts 130 may be inserted or removed transversely, and by placing the washers 137 and 141 in the corresponding recesses after the bolt has been inserted, displacement of the latter in a sidewise direction is prevented. The arrangement thus permits any of the bolts to be conveniently removed by merely loosening the nuts sufficiently to permit the washers to be taken out of the recesses after which the bolts may 80 be withdrawn from the radial slots.

The weight of the upper sections supplemented by the clamping action of the bolts 130 will ordinarily be sufficient to prevent any creeping of the grinding ring with possible angular displacement of the upper sections of the mill with respect to the base 12, but in order to prevent any such action there is provided a pair of stop blocks having the construction shown most clearly in Fig. 6. 90 Each of these devices comprises a block 142 provided with a depending hook portion 143 adapted to fit within the corresponding shaped socket 144 in the top of base 12. The grinding ring is provided with an exterior lug 145 adapted to serve as a stop for the end of the screw 146 passing through the block 142. By tightening the screw the hook portion of the block will be firmly engaged with the side of the socket within 100 which it is placed, thus preventing any displacement of the grinding ring relative to the base 12, it being understood that the parts will be so arranged relative to the direction of rotation of the grinding balls as to 105 cause the creeping tendency of the ring to force the lugs 145 more firmly against the ends of the screws 146. While in the embodiment of the invention shown herein two of the stop blocks are shown arranged at 110 diametrically opposite points of the mill, it will be understood that any other desired number may be used. The grinding ring is provided with one or more eye bolts 147 to which a rope or chain may be attached for 115 drawing the grinding ring out of the casing.

In the operation of the pulverizer mill described above, the main counter shaft 73 is driven from any suitable source of power and through the gears 83 and 84 drives the 120 main shaft 86 whereby the balls 118 will be propelled in the grinding ring 15.

A sufficient amount of oil will be placed in the cellar section of the mill to lubricate the bearings of the shaft and the gears connected between them. The oil cup 100 will maintain oil in the inner bearings of the main shaft at a suitable level to lubricate the entire bearing. The gland 110 will be suitably adjusted by manipulation of the 130

cams 111 to press the packing ring 109 against the bottom of bushing 105 to prevent leakage of oil from or entrance of dust into the bearing. The depending portion 5 of the yoke 115 which closely surrounds the upper bearing will also tend to prevent the entrance of any dust into the latter. At the same time the feeder will be driven by means of the belt 35 to cause the material to be fed 10 to the mill.

The pulverized material is lifted out of the zone of action of the grinding balls principally by the suction effect of the blades 119 which lift the material into the current 15 of air which enters the casing through the port section 17. On account of the contour of the outer edges 120 of the blades the material will be thrown toward the center of the mill so that relatively large particles will 20 fall back into the zone of action of the grinding balls, but the finer particles will be carried along by the air current produced by the fan 48 and from the latter into the conduit 41 leading to a separator.

25 The volume of air passing through the mill may be closely controlled by the ports in the wall of the damper and also by the ports in the bottom of the same. Further variation of the volume of air passing 30 through the mill may be effected by change in the sizes of one or more of the gears and pulleys in the driving connection to the fan. After the air has passed through the separator and has been relieved of its contents, 35 it returns through the conduit 20 to the return air chamber composed of the casing 19 and again enters the mill to pick up a fresh supply of pulverized material.

Whenever it is desired to repair or replace 40 any of the pulverizing elements of the mill access to the latter may be conveniently obtained through the door 24 which will be of sufficient size to permit any of the elements associated with the yoke 115 as well as 45 the yoke itself to be removed therethrough. After the yoke has been removed access may be had to the upper bearing of the main shaft, and the parts of the bearing may be removed through door 24 without disturbing 50 the main shaft 86 of the mill. Cleaning and replacing of internal parts of the mill may thus be conveniently performed, but in case it is necessary to remove the grinding ring the main counter shaft 73 is moved lengthwise 55 into the position shown in Fig. 3 to withdraw its inner end from the bearing 82 and disconnect the gear 83 from its companion gear 84. The free end of the shaft may be supported by placing the plate 71 upon a block 148. After the counter shaft 60 unit has been withdrawn the cellar section or gear housing which carries the main shaft and the bearings therefore may be lowered into the pit 11, it being understood that the 65 grinding balls, the lifting blades and the

yoke have been previously removed. The cellar section may be lowered by means of jacks or by long bolts temporarily inserted through the bolt holes in the base 12 or by any other suitable means, the sides of the 70 pit 11 being preferably provided with supports 149 upon which the cellar section may rest at the bottom of the pit.

To remove the grinding ring 15 the upper nuts of each pair 133 are loosened, and by 75 manipulation of the lower nuts of these pairs the entire upper portion of the mill may be elevated the desired distance. After this has been done two of the bolts at one side of the mill are removed as indicated in 80 Fig. 4, and the stop blocks 142 are disconnected by loosening the screws 146 and taking the blocks out of their sockets 144.

The grinding ring is then pried off of the base 12 until the ridge 16 is free. By means 85 of a suitable tackle attached to the eye bolt 147 the ring may then be drawn away from the mill. In case a new ring is to be inserted it is slipped between the base and the elevated upper sections of the mill until its 90 ridge 16 fits within the groove at the top of the base. The upper sections of the mill may then be lowered by manipulation of the lower nuts of the pairs 133 until these sections rest upon the top of the grinding ring, 95 after which the bolts which have been removed may be replaced as well as the stop blocks 142. The bolts 130 are then set to clamp the grinding ring in place, and the cellar section is lifted into its normal position and attached to the base 12. The counter shaft unit is then moved lengthwise 100 to insert the end of shaft 73 into its bearing 82 and bring the gears 83 and 84 into engagement.

105 In general the entire mill is so designed that the parts most liable to require cleaning or repairs may be reached without dismantling the entire mill, and the elements which require adjustment from time to time 110 such as the gland 110 and the cylindrical damper may be manipulated from the exterior of the mill. It also possesses the further advantage that even the grinding ring may be removed by a comparatively simple 115 operation requiring considerably less time and effort than in the case of a mill such as shown in my copending application in which it is necessary to lift the upper sections of the mill through a considerable distance and 120 also to disconnect the conduits leading to the separator.

While a preferred embodiment of the invention has been shown and described it will be understood that various changes in the 125 details of the construction may be made without deviating from the principle of the invention as defined in the appended claims.

I claim:

1. A pulverizer mill comprising a base, a 130

grinding ring mounted on the base, a casing mounted on the grinding ring and means connected between the base and the casing whereby the latter may be lifted to permit 5 the grinding ring to be laterally removed.

2. A pulverizer mill comprising a base, a grinding ring mounted on the base, a casing mounted on the grinding ring, and jacks connected between the base and the casing 10 whereby the latter may be lifted to permit the grinding ring to be laterally removed.

3. A pulverizer mill comprising a base, a grinding ring mounted on the base, a casing mounted on the grinding ring and bolts 15 connected between the base and the casing whereby the latter may be lifted to permit the grinding ring to be laterally removed.

4. A pulverizer mill comprising a base, a grinding ring mounted on the base, means 20 for holding the ring against lateral displacement, a casing mounted on the ring, means for holding the casing against lateral displacement, and means connected between the base and the casing whereby the latter may 25 be lifted to permit the grinding ring to be laterally removed.

5. A pulverizer mill comprising a base, a grinding ring mounted on the base, a casing mounted on the grinding ring and means for 30 clamping the grinding ring between the base and the casing and adapted to serve as jacks for lifting the casing to permit the grinding ring to be laterally removed.

6. A pulverizer mill comprising a base, a 35 grinding ring mounted on the base, a casing mounted on the grinding ring, and bolts for clamping the grinding ring between the base and the casing and adapted by manipulation of their nuts to be used as jacks for 40 lifting the casing to permit the grinding ring to be laterally removed.

7. A pulverizer mill comprising a base provided in its periphery with a plurality of radially disposed slots, a grinding ring 45 mounted upon the base, a casing mounted upon the grinding ring and provided in its periphery with a plurality of radially disposed slots, and bolts detachably mounted within the slots in the base and casing and 50 adapted by manipulation of their nuts to be used as jacks for lifting the casing to permit the grinding ring to be laterally removed.

8. A pulverizer mill comprising a base provided in its periphery with a plurality 55 of radially disposed slots and a recess concentric with each slot, a grinding ring mounted upon the base, a casing mounted upon the grinding ring and provided in its periphery with a plurality of radially 60 disposed slots and a recess concentric with each slot, bolts detachably mounted within the slots in the base and casing and adapted by manipulation of their nuts to be used as jacks for lifting the casing to permit the 65 grinding ring to be laterally removed, and

washers upon the bolts and adapted to lie within the recesses for holding the bolts in place.

9. A pulverizer mill comprising a base provided in its periphery with a plurality of 70 radially disposed slots having semi-circular inner ends, said base being also provided with circular recesses concentric with the inner ends of the slots, a grinding ring mounted upon the base, a casing mounted 75 upon the grinding ring and provided in its periphery with a plurality of slots and recesses similar to those in the base, bolts detachably mounted within the slots in the base and casing and adapted by manipulation of their nuts to be used as jacks for 80 lifting the casing to permit the grinding ring to be laterally removed, and circular washers upon the bolts and adapted to lie within the recesses for holding the bolts in 85 place.

10. A pulverizer mill comprising a base, a grinding ring mounted on top of the base, a casing mounted on top of the grinding ring, means connected between the base and 90 the casing whereby the latter may be lifted to permit the grinding ring to be removed, grinding balls in the ring, a housing detachably secured to the bottom of the base, a shaft mounted in the housing, and means on 95 the shaft for propelling the grinding balls.

11. A pulverizer mill comprising a base, a grinding ring mounted on top of the base, a casing mounted on top of the grinding ring, means connected between the base and 100 the casing whereby the latter may be lifted to permit the grinding ring to be removed, grinding balls in the ring, a shaft, means on the shaft for actuating the grinding balls, and a mounting for the shaft detachably secured to the base whereby the shaft 105 may be lowered through the ring to permit the latter to be removed edgewise from the mill.

12. A pulverizer mill comprising a base, a grinding ring mounted on top of the base, grinding balls in the ring, a shaft extending through the ring, means on the shaft for actuating the grinding balls, a member detachably secured to the base and provided 110 with bearings for the shaft, a casing resting upon top of the grinding ring, and means connected between the base and the casing whereby the latter may be lifted to permit the grinding ring to be removed sidewise 115 after the member carrying the shaft has been detached from the base and lowered to carry the shaft out of the path of the ring.

13. A pulverizer mill comprising a base, a grinding ring resting upon the base, grinding balls in the ring, a casing resting upon the grinding ring, means connected between the base and the casing for raising the latter to permit the grinding ring to be removed, a housing detachably secured to the base, a 120 125

main shaft mounted in the housing and extending through the ring, means on the shaft for propelling the grinding balls, a gear on the shaft, a counter-shaft having its 5 inner end supported in a bearing in the housing and provided with a gear engaging the gear on the main shaft, said counter-shaft being adapted to be moved lengthwise to disengage the gears and withdraw its inner 10 end from the housing to permit the latter to be lowered so that the main shaft may be withdrawn from the ring when the latter is to be removed from the mill.

14. A pulverizer mill comprising a base, 15 a grinding ring resting upon the base, grinding balls in the ring, a casing resting upon the grinding ring, means connected between the base and the casing for lifting the latter to permit the ring to be removed edge-wise, 20 means for propelling the grinding balls including a shaft extending through the ring, a mounting for the shaft detachably secured to the base so that it may be lowered to withdraw the shaft from the 25 ring when the latter is to be removed, and a driving connection for the shaft adapted to be disconnected therefrom when the mounting is to be lowered.

15. A pulverizer mill comprising a base, 30 a grinding ring resting upon the base, grinding balls in the ring, a casing resting upon the grinding ring, means connected between the base and the casing for lifting the latter to permit the ring to be removed edge-wise, 35 means for propelling the grinding balls including a shaft extending through the ring, a mounting for the shaft detachably secured to the base so that it may be lowered to withdraw the shaft from the ring when the latter is to be removed, and means for driving 40 the shaft including a counter-shaft geared thereto and adapted to be moved lengthwise to disconnect the gears when the mounting is to be lowered.

45 16. A pulverizer mill comprising a base, a grinding ring resting upon the base, a casing resting upon the grinding ring, means for preventing creeping of the grinding ring, and means connected between the base 50 and the casing whereby the latter may be lifted to permit the ring to be removed.

55 17. A pulverizer mill comprising a base, a grinding ring resting upon the base, a casing resting upon the grinding ring, means connected between the base and the casing whereby the latter may be lifted to permit the ring to be removed, and devices for preventing creeping of the grinding ring each comprising a hook adapted to fit within 60 a socket in the base, and means on the ring co-operating with the hook for preventing movement of the ring.

65 18. A pulverizer mill comprising a base, a grinding ring resting upon the base, grinding balls in the ring, means for propelling

the grinding balls, and means for preventing creeping of the grinding ring on the base due to the movement of the balls therein, comprising lugs on the periphery of the ring, hooks secured to the base and screws 70 in the hooks engaging the lugs whereby the hooks and screws resist movement of the ring.

19. A pulverizer mill comprising a base, a grinding ring resting upon the base, grinding balls in the ring, a housing detachably connected to the bottom of the base, a shaft, a lower bearing for the shaft mounted at the bottom of the housing, an upper bearing for the shaft mounted on top of the housing, 80 and a member carried upon the upper end of the shaft and provided with a plurality of arms for propelling the balls when the shaft is rotated.

20. A pulverizer mill comprising a casing, 85 means within the casing for pulverizing material, a conduit leading from the top of the casing and adapted to be connected to a separator, a fan at the top of the casing for forcing a current of air laden with pulverized material through the conduit, a cylindrical member mounted within the casing at the top thereof and provided with a bottom having a series of ports therein, a movable, circular member mounted upon the 95 bottom of the cylindrical member and provided with ports adapted to register with the ports therein, and means connected to the movable member and extending to the outside of the casing whereby the position 100 of the movable member may be adjusted to regulate the amount of air which may pass through the ports to the fan.

21. A pulverizer mill comprising a casing, 105 means within the casing for pulverizing material, a conduit leading from the top of the casing and adapted to be connected to a separator, a fan at the top of the casing for forcing a current of air laden with pulverized material through the conduit, a cylindrical member mounted within the casing at the top thereof and provided with ports in its wall and having a bottom provided with ports, a movable cylindrical member associated with the first named cylindrical member 110 and provided with ports adapted to register with the ports in the wall thereof, a circular member movably mounted upon the bottom of the cylindrical member and provided with ports adapted to register with the ports therein and means whereby the movable cylindrical member and the circular member may be independently adjusted from the outside of the casing to regulate the amount of air which may pass 120 through the ports to the fan.

22. A pulverizer mill comprising a casing, 125 a grinding ring, grinding balls in the ring, a shaft of abbreviated length at the bottom of the casing, a member mounted on 130

top of the shaft and provided with a plurality of arms for propelling the balls through the ring when the shaft is rotated, and inclined blades mounted in the member above the arms for lifting material out of the zone of action of the balls, said blades being provided with outer, vertical edges having a curvature adapted to deflect the material toward the center of the casing as it is lifted.

23. A pulverizer mill comprising a casing, a grinding ring, grinding balls in the ring, a shaft of abbreviated length at the bottom

of the casing, a member mounted on top of the shaft and provided with a plurality of 15 arms for propelling the balls through the ring when the shaft is rotated, brackets detachably mounted on the member, and inclined blades at the outer ends of the brackets having their outer edges bent upward and curved in a manner to deflect the material toward the center of the casing as it is lifted by the blades. 20

In testimony whereof I affix my signature.

HARRY RAYMOND COLLINS.
